UNITED STATES PATENT OFFICE.

AUGUST G. SANDMAN, OF BALTIMORE, MARYLAND.

CAR TRUCK.

1,410,516.

Specification of Letters Patent. Patented Mar. 21, 1922.

Application filed July 20, 1920. Serial No. 397,777.

To all whom it may concern:

Be it known that I, AUGUST G. SANDMAN, a citizen of the United States, residing at Baltimore, and State of Maryland, have invented certain new and useful Improvements in Car Trucks; and I do hereby declare the following to be a full, clear, and exact description of the invention, such as will enable others skilled in the art to which it applies to make and use the same.

The invention relates to railway cars and more particularly to car trucks therefor, and has for its principal object the prevention of destructive wear upon the car truck pedestal jaws and upon the journal boxes associated therewith. The said parts are subject to rapid and destructive wear caused by the constant movement of the journal boxes and equalizer bars with respect to the said pedestal jaws. To this end the main feature of my invention, generally stated, comprises wear plates adapted to be applied to each pedestal jaw in a simple and inexpensive manner, said wear plate being formed so as to interpose a wear resisting portion between the adjacent pedestal jaw and each moving part so as to protect the jaw from all wear. I also contemplate providing the journal boxes with wear plates to afford additional protection to the same and at the same time provide a smooth surface to cooperate with the wear plates on the pedestal jaws.

To these and other ends the invention comprises the various elements and combinations of elements hereinafter described the novel features whereof are set forth in the claims.

In the drawings,—

Figure 1 is a view half in side elevation and half in vertical section, the section being taken on line 1—1 of Fig. 2, of a passenger truck pedestal with the associated parts.

Fig. 2 is a transverse vertical section on line 2—2 of Fig. 1.

Fig. 3 is a view in front elevation on a slightly smaller scale of half of the truck pedestal with the coacting parts removed showing the improved form of wear plate in position.

Fig. 4 is a view partly in section of the construction shown in Fig. 3, the section being taken on line 4—4 of Fig. 3.

Fig. 5 is a transverse horizontal sectional view taken on line 5—5 of Fig. 3.

Fig. 6 is a top plan view of half of a journal box pedestal.

Fig. 7 is a transverse vertical sectional view taken on line 7—7 of Fig. 6.

Fig. 8 is a view in side elevation of the pedestal wear plate showing the same before the said plate is pressed into shape to fit the coacting jaw; and

Fig. 9 is a perspective view of the wear plate after the pressing operation is completed.

Throughout the specification and drawings like parts are designated by like reference characters.

The numeral 1 designates a portion of the truck side frame to which is connected the pedestal 2. Said pedestal comprises a pair of upright flanges 3 and 4 adapted to fit on opposite sides of the side frame 1 and to be bolted thereto in the ordinary or conventional manner. The inner and outer flanges 3 and 4 of the pedestal are connected by webs 5 which abut the under face of the frame 1, as clearly shown in Figs. 1 and 7, and extending downwardly from the said pedestal flanges and lying on opposite sides of the journal box 6, are the pedestal jaws 7. Each pedestal jaw preferably comprises spaced downwardly extending webs, 8, 8, which are connected adjacent their lower ends by the transversely extending web 9 and by the upright web 10 the outer face of which is parallel with the outer faces of the said flanges or webs 8. The opening in each pedestal jaw above the upper end of the upright web 10 is adapted to receive the end of the adjacent equalizer bar 11.

It might be here noted that in passenger car trucks and in some freight car trucks the spring members by which the truck body is resiliently supported on the car axles, is not immediately interposed between the top of each journal box and the adjacent portion of the side frame, but is interposed between the side frame or in some instances the body bolster and the journal boxes, by means of equalizer bars, the spring members being located in such position with reference to the side frame as to permit of greater capacity springs being employed than could be employed were the springs located immediately above the journal boxes. By employing equalizer bars the size of the cushioning units is not limited, and the character of the

truck side frame is much improved. These equalizer bars, which are designated in the drawing by the reference character 11, extend through the openings in each pedestal jaw and have their adjacent ends in substantial contact and are adapted to bear against the upper portion of the said journal box.

It will be readily apparent that the journal boxes, such as 6, which are mounted on the car axles so as to partake of all the movements thereof, will be caused to move with reference to the pedestal jaws 7 by the passage of a train over the various inequalities of the railroad track, such as cross-overs, switches and frogs. It will also be apparent that when braking pressure is applied to the car wheel the side walls of the journal box will be forced against one or the other of the pedestal jaws, depending upon the direction of movement of the train, with great force, and it will be readily appreciated that a grinding action will take place under these conditions upon a relative movement of the journal box with reference to the pedestal jaws. This relative movement between the journal boxes and the pedestal jaws causes rapid wear of the said pedestal and destructive wear upon the journal boxes. To overcome this wear I provide each pedestal jaw with a wear plate 12 preferably formed of pressed steel. The said wear plate may conveniently be manufactured from a sheet steel plate which is first cut or shaped to the form shown in Fig. 8 where it is seen that the plate is substantially rectangular and provided with a downwardly projecting lip or tongue 13, a pair of laterally projecting wings 14, 14, and a centrally disposed longitudinally extending slot 15 which, at its lower end, terminates in a Y or fork-shaped cut 16. The blank so formed may then be put into a suitable press, and the side members or wings 14 bent inwardly as are the portions of the plate which lie on opposite sides of the slot 15. The dotted lines 17 in Fig. 8 indicate the lines on which the portions of the plate are bent so as to form the said plate as clearly shown in Fig. 9. The flanges formed by the wings 14 extend substantially the full length of the said plate, while the flanges 18 formed by bending the intermediate portions of the plate along the dotted lines 17 terminate at a suitable distance from the lower edge of the said plate. The projecting lip or tongue 13 at the lower end of the plate is also bent or curved inwardly and upwardly as best shown in Figs. 1 and 9. The plate so formed is now ready to be applied to the pedestal jaw. It will be noted that the distance between the lowermost portion of the tongue 13 and the lower ends of the diagonal cuts 16 is substantially equal to the height of the vertical web 10 which connects the lower portion of the pedestal jaws. The transversely extending

web 9 of each pedestal jaw is provided with a downwardly projecting rounded shoulder 19 which is adapted to fit within the lip formed by the inward bending of the flange 13.

70

To apply the pedestal liner or wear plate the journal box is removed and the liner forced or driven into a position so that the upper edge of the lip 13 lies below the shoulder 19 on the flange or web 9. In this position the vertical webs 8 of the pedestal jaw extend between the flanges 13 and 18 formed in part by the wings 14. The plate is then driven upwardly and inwardly until the lip 13 is in contact with the lower face of the shoulder 19 and the main web or plate is in tight contact with the outer face of the web 10 and the outer faces of the webs 8. To maintain the plate in this position the tongue 20 formed by the diagonal cuts 16 is bent inwardly over the upper edge of the flange or web 10 and then downwardly behind the same, as clearly shown in Fig. 1, so as to closely embrace the upper extremity of the flange 10. By this means the plate or liner is maintained in position without the use of rivets or other fastening means, and is readily removable in case of necessity. It will be noted that the inwardly extending flanges 18 of the said plate 12 lie on opposite sides of the equalizer bar 11 and protect the inner faces of the flanges 8 from wear due to the movement of the equalizer bars.

75

Each journal box 6 is preferably provided with a wear plate 21 against which the inner ends of the equalizer bars 11 are adapted to bear, and each equalizer bar may be provided at its inner end with a wear plate 22 which may be retained in position thereon by spot welding the same to the equalizer bar.

90

The pedestal guideways 23 formed in the side walls of the journal box may likewise be protected from wear by employing pressed steel wear plates 24, and these wear plates may be retained in position by forming either the upper or the lower portions thereof with an inwardly extending curved portion 25, and providing the opposite end of the wear plate with a bendable or ductile tongue 26, which may be bent over the shoulder 27 formed on either the upper or the lower walls of the journal box to thereby maintain the journal box wear plates in position. In case the journal boxes are provided with offsets 28, such as are shown in Fig. 1, so as to clear the particular form of equalizer bar 11 shown in said figure, the intermediate portions of the journal box wear plates may be cut away as at 29 to prevent contact of the same with the equalizer bars.

100

Having now described my invention, although it is to be understood that the terms employed are to be taken in their descrip-

110

115

tive and not their limiting sense, what I claim is:—

1. The combination with a car truck, of a pedestal mounted thereon, said pedestal being provided with a pair of spaced jaws, a liner plate adapted to be applied to each pedestal jaw, and means integral with said plates for connecting the same to the respective pedestal jaws, said means being adapted to extend within a recess in the adjacent jaw.

2. The combination with a car truck, of a pedestal connected thereto, said pedestal having a pair of spaced jaws, a journal box slidably mounted between the said jaws, and means comprising a wear plate interposed between each jaw and the said journal box, said plates having portions adapted to interlockingly engage the adjacent jaw at a plurality of points and connected to the former for preventing wear upon the said jaws, said plates being maintained in position independent of the means for supporting said journal boxes.

25 3. The combination with a car truck, of a pedestal connected thereto, said pedestal being provided with a pair of spaced jaws, equalizer bars associated with said pedestal

and each adapted to extend through an opening in one of the said jaws, and means 30 connected to the said pedestal jaws and interposed between the same and the adjacent equalizer bar and adapted to protect the said jaws from wear.

4. The combination with a car truck, of 35 a pedestal connected thereto, said pedestal having a pair of spaced jaws, liner plates adapted to overlie the adjacent faces of the said jaws, and means integral with each liner plate and adapted to embrace a portion of the adjacent jaw to maintain said liner plates in assembled position, each plate also having flanged edges engaging the lateral edges of the adjacent jaw.

5. The combination with a car truck, of 40 a pedestal connected thereto and provided with spaced jaws, each of said jaws having upright webs connected adjacent the lower portions thereof, wear plates adapted to overlie said pedestal jaws, each of said plates 45 having channels therein to receive the said upright webs, and means integrally formed on each of said plates for connecting the same to the said adjacent pedestal jaw.

In testimony whereof I affix my signature. 55

AUGUST G. SANDMAN.
